CLAIM

The ornamental design for a sanitizing toothbrush cabinet, as shown and described.

DESCRIPTION

FIG. 1 is a perspective view of the sanitizing toothbrush cabinet showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof;

FIG. 7 is a left elevation view thereof;

FIG. 8 is a perspective view thereof, with the hinged closure in an alternate position; and,

FIG. 9 is a perspective view thereof, with the hinged closure in an alternate position and showing the ultra violet light. Broken lines are included for depicting environmental subject matter and form no part of the claimed design.
